N. S. HILLYARD

LIQUID RECEPACLE

Filed Aug. 21, 1926

Patented Jan. 3, 1928.

1,654,810

UNITED STATES PATENT OFFICE.

NEWTON S. HILLYARD, OF ST. JOSEPH, MISSOURI.

LIQUID RECEPTACLE.

Application filed August 21, 1926. Serial No. 130,660.

My invention relates to liquid receptacles, and more particularly to a liquid dispensing receptacle.

It is a purpose of my invention to provide a portable liquid dispensing receptacle that is adapted for use in dispensing liquid soap or similar material in hospitals or similar places where it is desired to move the receptacle from place to place instead of maintaining the same in a permanent position on a wall as is customary with devices of this character.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a perspective view of my improved dispensing receptacle in upright position.

Fig. 2 is a similar view thereof in dispensing position.

Fig. 3 is a view partly in elevation and partly in section of the device in the position shown in Fig. 1.

Fig. 4 is a fragmentary sectional view taken substantially on the line 4—4 of Fig. 3, and

Fig. 5 is a fragmentary perspective view of a portion of the base and handle members showing the same separated from the base and the securing means therefor.

Referring in detail to the drawings: my improved portable dispensing liquid receptacle comprises a base member 10 which is provided with a metal cover plate 11 having a down-turned flange portion 12 connected with the top portion thereof by means of a bevelled portion 13. A handle member 14 is secured to the base member 10 by means of the screw-threaded securing members 15 which have heads 16 seated in counter-sunk openings 17 in the base member 10 and a layer of felt or similar material 18 is secured to the under side of the base 10 covering the heads 15 of the said members 16. The securing members 16 screw-threadedly engage in openings 19 in the handle member 14, said handle member having substantially

straight parallel upstanding portions 20 which are connected by means of the bowed portion 21. The upstanding portions 20 are provided with screw-threaded openings 22 receiving the reduced screw-threaded portions 23 of pivot members 24 which have enlargements 25 thereon, engaging with the members 20 and providing shoulders 26 for limiting axial movement of the receptacle relative to the pivot members.

Mounted between the upstanding portions 20 of the handle in spaced relation to the bowed portion 21 thereof and the base member 10 is a substantially cylindrical liquid receptacle having a substantially cylindrical glass body portion 27 which is provided with inwardly bowed portions 28 forming recesses 29 in the end walls thereof offset from the axis of the cylindrical wall portion of the receptacle which align with openings 30 provided in the metal cap members 31 mounted on opposite ends of the cylindrical glass member 27, said openings 30 being formed by a punching operation thus forming a sleeve-like extension of the material of the cap member directed inwardly toward the recesses 29 and embracing the pivot member 24 extending therethrough. The cap members 31 are made of metal and have the curved edge portions 32 terminating in inwardly turned hook-like flanges 33 that seat in the circumferential grooves 34 cast in the glass body portion 27. It will thus be seen that the receptacle is pivotally mounted on an axis eccentric to the longitudinal axis of the same on the handle member 14.

The liquid receptacle is provided with a dispensing nozzle which operates in substantially the usual manner, said dispensing nozzle being mounted on the outwardly extending boss 35 cast on the member 27 to which the metal sleeve 36 having the screw-threaded portion 37 formed thereon is cemented or otherwise secured. Screw-threadedly engaged with the threaded portion 37 is the threaded portion 38 on the cap member 39, said cap member having a tubular member 40 extending into the receptacle therefrom which is provided with a plurality of openings 41 therethrough and which is open at the lower end 42 thereof and which has a valve member 43 slidable therein. The valve member 43 controls the flow of liquid 44 from the receptacle having a valve portion 45 adapted to engage with the valve

seat 46 which controls the flow of liquid through the longitudinal passage 47 and the transverse passage 48 in the outwardly projecting end portion 49 of the dispensing nozzle.

The dispensing nozzle operates in an obvious manner dispensing a predetermined quantity of liquid upon tilting of the receptacle from the position shown in Fig. 1 to the position shown in Fig. 2. In order to facilitate tilting of the receptacle on its axis an operating member 50 is cast in the glass body portion 27 of the receptacle running lengthwise thereof and having a substantially perpendicular face 51 on one side thereof and a bevelled face 52 on the other side thereof. The person to whom soap is to be dispensed, for example, may operate the same by pushing downwardly on the right-angular face 51 of the operating member 50 with the finger tips, thus tilting the same to the position shown in Fig. 2 when the liquid will run from the end of the nozzle into the cupped hand of the operator.

25 Due to the eccentric mounting of the recep-

tacle the same will be overbalanced in the position shown in Fig. 2 and will return to its upright position due to the action of gravity.

What I claim and desire to secure by Letters Patent is:—

1. A device of the character described comprising a substantially cylindrical glass receptacle having recesses in the end walls thereof and having circumferential grooves adjacent said end walls, and metallic caps on the ends of said receptacle having flanges entering said grooves and having pivot pin openings aligning with said recesses. 35

2. A container device for pivotal mounting on a frame having spaced supports provided with pivots, comprising a receptacle having opposite wall provided with recesses to receive the pivots, and caps on the opposite wall portions of the receptacle having pivot pin apertures aligned with said recesses through which the pivot pins project into said recesses. 40 45

In testimony whereof I affix my signature.

NEWTON S. HILLYARD.
